UNITED STATES PATENT OFFICE

2,048,569

ICE CRUSHER

Herbert C. Johnson, Chicago, Ill.

Application May 24, 1934, Serial No. 727,307

4 Claims. (Cl. 83—63)

My invention relates to ice crushers and it has to do more particularly with a portable device of this character adapted for household, and the like, use.

5 One of the objects of my invention is to provide a device of the foregoing character which is simple in construction, is inexpensive to manufacture, is of light weight, and is exceedingly strong and durable.

10 Another object is to provide an ice crusher well adapted to receive and crush comparatively small pieces of ice in cube, or other, form without the necessity of applying to the ice force other than that afforded by the weight of the ice; whereby 15 the ice may be crushed quickly without particular care, skill and attention on the part of the user.

10 Another object is to provide an ice crusher having movable crushing members or jaws which engage the ice with a claw-like action so as to 20 positively move the ice into and hold it in crushing position.

25 A more specific object is to provide an ice crusher having a rotatable crushing unit embodying a plurality of hook-like crushing fingers which both hold and crush the ice, which unit is adapted for reciprocation during rotation to aid in the crushing operation and discharge of the crushed ice.

30 Other objects and advantages will appear as the following description progresses and by reference to the drawing wherein.

Figure 1 is a top plan view of one form of structure, embodying my invention;

35 Fig. 2 is a section taken substantially on line 2—2 of Figs. 1 and 3 and showing the parts in an ice crushing position;

Fig. 3 is a section taken substantially on line 3—3 of Fig. 2; and

40 Fig. 4 is a fragmental sectional view taken at substantially the same position as Fig. 2, but showing the parts in position prior to the crushing action.

45 The ice-crushing device shown in the drawing is of a portable character particularly suited for household use. It will be understood, however, that devices of this character embodying my invention may well be employed in other places where its advantages are desired such, for example, as soda fountains, clubs, hotels, and other 50 beverage dispensing places. Also, while the form shown in the drawing is readily portable, the structure may, if desired, be fixedly secured to a permanent support without departing from my invention.

55 Referring particularly to the drawing, the

structure shown includes a bowl or receptacle 10 which has an upper or ice-receiving opening 11 and a bottom or ice-discharging outlet 12. The receptacle 10 is provided with a rearwardly-offset boss 13 in which the upper end of an upright 5 supporting post 14 is secured. The receptacle 10 is formed, preferably, by casting and it is secured to the upper end of the post 14 by casting the same upon the latter, the knurled or roughened post portions 15 being provided to insure 10 fixed securement of these parts together.

The post 14 is supported by a base 16 that is provided with an upstanding boss 17 having an opening therein to snugly receive the lower end of the post 14. The post 14 is secured to the base 15 16 by a screw 18 applied, as shown, through the base recess 19.

The base 16 is of such size and shape that it supports the receptacle 10 without danger of the latter tipping over when the ice is being crushed. 20 This base is provided with a pair of forwardly-extending arms 16^a and 16^b joined by a web portion 20 having an open-top socket 21 therein for supporting a tumbler or other ice-receiving vessel 22 directly beneath the receptacle outlet 12.

It is quite customary for ice to be formed in the home and elsewhere by means of refrigeration devices. This ice is usually formed in trays, or the like, in a plurality of comparatively small 30 pieces usually of cube form. It is desirable in many instances, for the sake of convenience, as well as to avoid waste, to break up the ice thus formed into smaller pieces. My invention is particularly adapted for crushing ice cubes and the 35 like; but it is to be understood that it also has utility in the crushing of ice in any form that may be inserted within the receptacle 10.

It has been found that, in the crushing of pieces of ice of the foregoing character, particularly 40 where rotating, crushing elements are employed, difficulty is experienced in feeding the ice into and holding it in crushing position. Due to the hardened condition of the ice, rotating elements tend to throw the ice away from the crushing elements, unless this is particularly guarded against.

45 My invention overcomes the foregoing difficulties and provides an ice crushing means of a rotatable character which is adapted to pierce and grippingly engage the pieces of ice and drag them 50 into and hold them in crushing position while the crushing operation is taking place.

To the foregoing end, the lower portion of the rear wall 23 of the receptacle 10, slightly above the outlet 12, is provided with a plurality of 55

spaced ribs or jaws 24 extending longitudinally of the receptacle. The opposite side walls 25 and 26 of the receptacle above the jaws 24 are provided with comparatively large openings which 5 snugly receive rotatable bearing members 27 and 28, the bearing member 27 having a handle extension 29 by which such bearing member may be rotated.

The bearing members 27 and 28 are provided 10 with reduced, inwardly extending and eccentric hub portions 27' and 28' that support the opposite ends of a poly-sided (preferably hexagonal) shaft 30. One end of this shaft 30 has, preferably, the bearing member hub 27' cast thereupon 15 while the other end of such shaft is non-rotatably received in a recess in the bearing member hub 28'. The latter end of the shaft 30 is detachably secured to the bearing member 28 by a screw 31. The outer parts of the bearing members 27 and 28 20 are slightly enlarged to provide shoulders 32 and 33 that seat upon the outer surfaces of the side walls 25 and 26; whereby the shaft and bearing member assembly 27-28-30 is rotatably secured to the receptacle. The shaft 30 is mounted eccentrically with respect to the bearing members 27 and 28 so that the shaft 30 is given a linear or 25 reciprocatory movement as it is rotated.

The shaft 30 supports a plurality of crushing jaws or fingers 34, 35, 36, 37, and 38. These fingers are of comparatively thin, blade-like form. One end of each finger is provided with an opening of the size and shape of the shaft 30 so that they may be passed thereover and held against rotation. These fingers are mounted in predetermined spaced relation with respect to each other by the bearing hubs 27' and 28' and by sleeve members 39, 40, 41, and 42; and the fingers are so positioned along the shaft by the sleeves and hub members that they rotate in planes extending between the stationary jaws 24 and between the outermost of these jaws and the adjacent receptacle walls 25 and 26.

The rotatable jaws or fingers 34 to 38 are of hook or claw-like form. They are of such shape 45 that they extend tangentially away from the shaft 30 and they each taper and curve into a claw-like end portion which is sufficiently sharp-pointed to piercingly engage the ice.

Furthermore, the fingers 34 to 38 are arranged 50 to successively engage the ice as well as to successively move into crushing position. Specifically, I preferably mount the middle finger 34 so that it will assume the downward and crushing position when the handle 29 is in its normal downward position of rest (Fig. 3). The intermediate fingers 35 and 36 are mounted in the same position approximately 60 degrees around the shaft 30 rearwardly (with respect to direction of rotation) of the finger 34 and the outer fingers 37 55 and 38 are located in the same position approximately 60 degrees rearwardly of the fingers 35 and 36. The hexagonal shape of the shaft 30 aids in this particular positioning of the fingers; but it is to be understood that the relative circumferential spacing of the fingers, as well as the number of fingers, may be varied somewhat without departing from my invention. With the arrangement of the fingers shown in the drawing, the fingers will assume substantially the position shown 60 in Fig. 4 as the handle 29 is moved to an upright position and as the ice is being gripped for the crushing action.

The operation and advantages of my invention will be readily understood from the foregoing. 70 The ice to be crushed may be dropped into the

receptacle when the handle 29 is in the position shown in Fig. 3. As the handle is rotated from its Fig. 3 position to the position shown in Fig. 4, the fingers 34 to 38 are rotated and the shaft 30 is simultaneously reciprocated upwardly. In this 5 movement, the finger 34 raises and then grabs the ice and tends to move the same forward and downward toward the stationary jaws 24. As the rotation of the handle is continued, the fingers 35 to 38, successively engage the ice and hold the 10 same in crushing position while the crushing action is taking place. Due to the action of the rotatable fingers, the foregoing is carried out without the necessity of using the hand or other object to hold or force the ice into crushing position. The rotatable fingers in conjunction with the jaws 24 crush the confined ice in a manner which will be well understood. This crushing action is materially aided by the linear or transverse or reciprocatory motion of the shaft 30 and 20 fingers 34 to 38 during the rotation of these parts. The crushed ice is discharged through the bottom receptacle opening 12.

I have found that the structure embodying my invention is highly efficient for ice crushing purposes. It is quite simple and it may be very cheaply manufactured. Such structure is, also, exceedingly strong and durable. It embodies a minimum of operating parts, all of which may be readily and easily and cheaply replaced.

It will be understood that while I have shown and described only one form of structure embodying my invention, other changes in details and arrangements of parts may be made without departing from the spirit and scope of my invention as defined by the claims which follow:

I claim:

1. In an ice crusher, a receptacle having an outlet in its bottom, five claw-like crushing fingers mounted above said outlet, and means for mounting said fingers including a shaft upon which said fingers are non-rotatably secured in spaced relation with respect to each other and the receptacle walls, rotatable members carried by opposite side walls of said receptacle and to which the opposite ends of said shaft are non-rotatably secured in eccentric relation with respect thereto, one of said rotatable members being detachably removable from said shaft, said fingers being so positioned on said shaft that the middle finger is offset forwardly from the next adjacent or intermediate fingers and the two outside fingers are offset rearwardly from the intermediate fingers.

2. In an ice crusher, a receptacle having an outlet in its bottom, five claw-like crushing fingers mounted above said outlet, and means for mounting said fingers including a shaft upon which said fingers are non-rotatably secured in spaced relation with respect to each other and the receptacle walls, rotatable members carried by opposite side walls of said receptacle and to which the opposite ends of said shaft are non-rotatably secured in eccentric relation with respect thereto, one of said rotatable members being detachably secured to said shaft, and means associated therewith to prevent endwise movement of said shaft, said fingers being so positioned on said shaft that the outer or first and fifth thereof are aligned with each other, the second and fourth or intermediate thereof are aligned with each other and are offset around said shaft from said outer fingers and the third or middle finger is offset around said shaft from all said other fingers.

3. In an ice crushing device including a receptacle, a crushing unit which comprises a pair of

comparatively large bearing members adapted to be rotatably mounted and supported by the opposite side walls of the receptacle, a comparatively small poly-sided shaft having its opposite ends 5 eccentrically secured to said bearing members, one of said bearing members being detachably secured to said shaft and having means in engagement with the side wall to prevent transverse movement of said shaft upon its rotation, a plurality of 10 blade-like crushing fingers having one end mounted upon said shaft and being so shaped that their other ends are sharp-pointed and extend away from said shaft in hook-like fashion, and means mounted on said shaft for holding said 15 fingers in spaced relation with respect to each other so that their comparatively narrow forward edges, with respect to direction of rotation, engage the ice, said fingers being so positioned on said shaft that some of them engage the ice in 20 succession.

4. In an ice crushing device, a crushing unit which comprises a pair of comparatively large

bearing members adapted to be rotatably mounted, a comparatively small hexagonal shaft having one of its ends permanently secured to one of said bearing members and its opposite end eccentrically mounted and detachably secured to the other of said bearing members and having means for securing said shaft against transverse movement upon its rotation, bearing members, a plurality of blade-like crushing fingers each having a hexagonal opening in one end thereof adapted to snugly receive said shaft, said fingers being so shaped that their other ends are sharp-pointed and extend away from said shaft in hook-like fashion, and means mounted on said shaft for holding said fingers in spaced relation with respect to each other so that their comparatively narrow forward edges, with respect to direction of rotation, engage the ice, said fingers being so positioned on said shaft that some of them engage the ice approximately 60 degrees in advance of each other. 5 10 15 20
